METHOD AND MEANS FOR DISINTEGRATING PULP STOCK

Filed Aug. 10, 1929

Inventor.
Harry Liebeck.

By John H. Nichols
Attorney.

UNITED STATES PATENT OFFICE

HARRY LIEBECK, OF SWARTHMORE, PENNSYLVANIA, ASSIGNOR TO SCOTT PAPER COMPANY, A CORPORATION OF PENNSYLVANIA.

METHOD AND MEANS FOR DISINTEGRATING PULP STOCK

Application filed August 10, 1929. Serial No. 384,820.

The object of my invention is to provide a method and means adapted to thoroughly disintegrate wood and other pulp in baled condition into paper stock in which the pulp is so fully subdivided that it is suitable for use in the head box of a paper making machine.

A further object of my improvements is to provide a disintegrating machine for handling pulp upon a large scale and with a minimum labor requirement and low cost.

My invention comprises a large tank, preferably of concrete, containing water and having an inlet at the top through which wood or other pulp in baled condition may be deposited in its entirety (or in any other condition available on a large scale) into the water content of the tank, the said tank having at its bottom or lower part a screened outlet through which those portions of the pulp which are sufficiently subdivided may flow or be drawn off and, with or without further subdividing treatment, delivered to the head box of a Fourdrinier machine or to the tank of a cylinder type paper making machine, and wherein the disintegrating tank is provided with a rotating shaft to which are secured a plurality of sturdy propellers operating to disintegrate and subdivide the pulp into a condition suitable for use in a paper making machine, the said disintegrating propellers being preferably so arranged within the tank that the flow of the currents due to them oppose each other and thereby cause a similar opposed flow of the pulp stock therein, to insure a more intimate mixture of the pulp particles during their treatment.

My improved apparatus further comprises properly positioned baffle plates extending transversely of the tank chamber and respectively above or out of alignment with the opposing propellers, with the result that the water and its associated pulp is caused to be brought into intimate contact and put under forced recirculation upward and over the baffles, thence downward beyond the baffles, to be again acted upon by the disintegrating propellers.

My invention also comprehends minor

features of construction which, together with those above stated, are more fully described hereinafter and pointed out in the claims.

Referring to the drawings: Fig. 1 is a plan view of a pulp disintegrating apparatus; Fig. 2 is a vertical section of the same, taken on line 2—2 of Fig. 1; Fig. 2a is a vertical section of a modified form of pulp disintegrating apparatus; and Fig. 3 is a side view of a modified form of disintegrating propeller.

2 is a large concrete tank or vat, the same formed with filled corners 4 and 4a to prevent portions of the pulp from being held in corner pockets and thus removed from circulation. The tank or vat is provided centrally of its upper wall 3 with an intake port 5 through which the bales of pulp are thrown to be subjected to disintegration within the tank, the same being received upon the water which fills the tank to approximately three-quarters of its vertical depth. The bottom of the tank is provided with a discharge opening 6 whose upper part is covered with perforated plates 8 abutted at a slight angle 75 and received in shouldered portions 9 of the concrete to position them and prevent them from spreading.

The support of the inclined plates 8 may be further assured by oppositely inclined supporting surfaces preferably formed in concrete, as indicated at 10, such supporting portions being arranged at opposite sides of the opening 6. The size of the openings through the plates 8 determine the fineness of the pulp subdivision or disintegration before it can pass from the tank 2 in which the disintegration takes place.

The water and pulp from the discharge opening 6 is conveyed therefrom by a pipe 12 90 which may deliver its contents to any place desired. As shown, it delivers into the suction pipe 13 through a suitable valve 11. The suction pipe 13 connects with the intake of a suitable pump 14, whose delivery is 95 through a pipe 15 leading to the head box of a paper making machine or to any other apparatus such as a "Jordan" (not shown) for further subdivision of the pulp.

As the fluid with the pulp in suspension is

continually passing out of the tank 2 through the pipe connections, suitable means for admitting additional water to the tank or vat 2 is provided, as indicated at 26. In this manner, the water level is maintained at the desired height.

- Arranged longitudinally of the tank 2 and in its lower portion is a propeller shaft 16 journaled at 17 at one end of the tank and 10 extending through a stuffing-box 18 at the other end, said shaft coupled with an electric or other suitable motor 25 whereby the shaft may be rapidly rotated. Secured upon the shaft 16 are a plurality of disintegrating 15 propellers 19 and 20. The propellers 19 have their blades at such an angle as to force a strong circulation of the fluid contents of the tank in a direction indicated by the arrows and hence toward the middle of the tank. 20 The propellers 20 are likewise secured to the shaft 16, but have their blades arranged at a different obliquity to that employed in the propellers 19 and so as to propel the fluid contents in the opposite direction, as indicated 25 by the arrows, and, therefore, the fluid currents from these two sets of propellers are driven toward each other with great violence and cause a thorough commingling of the fluid contents acted upon by the propellers applying pressure thereto to force the fluid 30 through the perforated plates 8 downward through the discharge and at the same time causing other portions of the violently moving fluid contents to rise upwardly within the 35 middle of the tank, at 23, and to return in opposite directions toward the end portions of the tank, and thence downward to be again operated upon by the propellers.

To facilitate the proper circulation of the 40 fluid contents by the propellers, I prefer to arrange above them transverse baffle plates 21 and 22, the planes of which baffles are substantially parallel to the shaft 16, said baffle plates providing between their under-surface 45 and the bottom of the tank tunnels or passages 16a in which the propellers are arranged and, at the same time, provide the space 23 between these tunnel portions and ends of the baffle plates and communicate with the upper 50 portion of the tank, whereby the fluid contents may flow from said central passage 23 in opposite directions above the baffle plates and thence downward through vertical passages 24, to be again acted upon by the propellers.

The upper wall or roof 3 of the tank 2 may 55 be made flat, as shown, to facilitate the conveyance and depositing of the pulp bales into the tank, and to this end a suitable bridge or runway 27 may extend to the top of the said 60 tank whereby a helper may wheel the bales supported by a truck into position for discharge into the intake opening 5, such a helper being indicated at 28. It will be understood that any of the well known forms 65 of chain conveyers may be utilized for charg-

ing the tank with the pulp bales, if so desired, in place of manual labor, and I, therefore, do not limit myself in this respect.

It is to be further understood that I do not limit myself to any special shape or manner of constructing the tank nor as to its size or proportions, but prefer a tank of approximately thirty feet in length, fourteen feet high, and eleven or twelve feet across.

The propellers 19 and 20 may be more or less similar to ship propellers, but the blades thereof may be formed with sharper edges, and if desired, may have the edges of the blades serrated and sharp, as indicated at 20a in Fig. 3, said serrated edges acting to more quickly disintegrate the pulp, the serrations being directed toward the approaching currents of water and pulp. The pitch angle of the blades would be less where the speed of rotation of the shaft was very great, but where the speed is less the pitch of the screw may be increased.

As shown, the propellers are arranged in two groups, namely, those indicated by the numeral 19 and those indicated by the numeral 20, the former being arranged in the tunnel under the baffle plate 21, whereas the propellers 20 are arranged in the tunnel under the baffle plate 22. I, however, do not limit myself to the number of propellers, as one or more may be employed in each set.

The operation of the apparatus will now be understood. Assuming that the propellers were in full action, the fluid contents of the tank will be put into violent circulation and as the same approaches the middle of the tank from each end, the impact of the fluid under the action of the propellers will force it upward through the central passage 23 and this again will be facilitated by the inclined perforated plates 8 at the bottom of the tank, the inclination of which plates will cause the fluid content to flow upward and thereby positively assist in the upward circulation. The fluid contents in the upper part of the tank will, therefore, be in a high state of agitation and the bales of pulp discharged into the tank will become buffeted and put into circulation so as to be torn to pieces by the action of the propellers, and this action will be greatly facilitated by the absorption of moisture by the pulp. The agitation is continued so long as any pulp is to be disintegrated to a condition capable of passing through the apertures in the plates 8. It will also be understood that where the requirement for paper stock is continuous, this disintegrating machine may be kept running continuously and be supplied with pulp from time to time, as may be required.

The paper stock passing off from the disintegrating tank through the outlet 6 and pipe 12 will be compensated for by additional water from the water pipe 26 and further pulp, as may be required.

By reason of the simultaneous double cir-

5 culation of the pulp content, the same is not only disintegrated by each contact with the propellers, but the two currents of pulp are caused to forcibly impact upon each other at 10 a place of great physical disturbance, whereby not only is the disintegration facilitated, but the fluid content with its pulp stock is caused to intermingle in such a thorough manner that stock which may be acted upon by 15 the propellers 19 may be, on its next circuit, partly acted upon by the propellers 20, so that a thoroughly uniform treatment will be had of all of the fluid content and associated pulp stock within the tank.

15 The passages 16a below the baffle plates 21 and 22 constitute tunnels in which the propellers are located and for the passages of the water and pulp which are to be acted upon by the propellers. By reason of the confining 20 action of the walls of these tunnel portions, the pulp is assured proper disintegration by the propellers. Moreover, the rapid movement of the water and pulp through the tunnel portions 16a increases the violent action 25 of these meeting currents at the middle of the tank, so that the upward rush of the water and pulp increases the disintegration and violently acts upon the incoming fresh pulp to prepare it for the disintegrating action of 30 the propellers. The baffle plates 21 and 22, while forming the upper walls of the tunnels 16a, and insuring the proper circulation, also act as binders or reinforcing means for the vertical walls of the tank and thereby greatly 35 strengthen them.

While the circulation of the two currents in opposite directions to provide the violent agitation at the middle of the tank is most important, it will be understood that the rotation of the propellers 19 and 20 will, in addition, cause rotation of the currents of water and pulp and churn them up during their flow through the tunnels or passages 16a so that the disintegrating effect upon the pulp 45 will be greatly enhanced by this additional action upon the fluid contents of the tank.

While I prefer to employ one or more baffle plates 21 and 22 with two sets of disintegrating propellers 19 and 20, and with the 50 propellers 19 and 20 operated by a continuous shaft as shown, I do not restrict myself in this respect, because the baffle plates may be omitted, if desired, and the two sets of disintegrating propellers 19 and 20 mounted 55 upon separate shafts 16c and 16d and respectively driven by independent motors 25 and 25a, as shown in Fig. 2a. The advantage of the baffle plates is to insure directive currents in the fluid, and hence more violent disintegrating action, and also because the breaking down of the pulp material is more rapidly 60 done than would take place without the use of baffle plates. Furthermore, the violent action upon the pulp stock due to the directive action of these baffle plates enables the

disintegration to be performed more quickly and with less consumption of power and hence more economically.

Moreover, the employment of two shafts and separate motors therefor permits the two 70 sets of disintegrating propellers to be operated at relatively different speeds to provide different speeds of circulation, or to insure corresponding circulations with different sizes and pitches of propellers, as may be 75 found desirable; and in the final stage, the completed product may be kept in circulation by use of one set of propellers and one motor only.

When the disintegrating treatment of the 80 pulp is carried to completion before discharging the pulp stock to the paper making machine, the screens 8 may be omitted, but where the process is continuous the screens 85 are desirable.

While the object of my invention is more particularly to treat wood pulp for use in the making of more or less inexpensive characters of paper, I do not restrict myself in this respect, as the improvements are adapted 90 for disintegrating pulp of any character suitable for paper making.

I have described my improved method and means in that particularity which I deem to be the best exposition of my invention and 95 that which I prefer in commercial practice, but I do not restrict or confine myself to the minor or secondary details, as such are susceptible of modification, which may be resorted to as matters of mechanical skill and 100 without a departure from the spirit of the invention.

Having now described my invention, what I claim and desire to secure by Letters Patent is:

1. The herein described method for disintegrating pulp in the making of paper pulp stock for paper making machines, which consists in creating rapidly moving opposed currents of paper making pulp and water and thereby causing violent intermingling and agitation of the said currents of paper pulp and water, causing the violently agitated fluid bodies thus provided to act upon a mass of pulp material in a more or less dry condition and thereby induce a preliminary softening and disintegration thereof and for carrying the said pulp into circulation, thereafter subjecting the softened pulp to a mechanical disintegrating action to more thoroughly break down the pulp and cause it to be intermingled with other fluid content to form a more or less homogeneous mixture, and continuing the treatment of mechanical disintegration whereby a desired subdivision 110 of the pulp is obtained.

2. The method stated in claim 1, wherein further, an upward rushing of the fluids above the normal fluid level when devoid of currents is caused by the violent agitation of 115

the fluid currents produced by propelling a plurality of the fluid currents toward each other.

3. The method according to claim 1, wherein further, the opposing currents comprise two currents forcibly moving in opposite directions through confining passages in the same alinement, and the opposing currents are also given a rotation transversely of 10 their direction of flow for increasing the violent agitation of the water and pulp.

4. In apparatus of the character stated, the combination of a fluid containing tank having an inlet at the top and an outlet below the fluid level therein, oppositely acting 15 disintegrating propellers rotating within the tank for producing violently opposed currents of the fluid therein, and wherein further, the tank is provided with transverse 20 baffle plates above the propellers and said baffles separated at the middle portion of the tank and from the ends of the tank, whereby the circulating fluid is commingled and forced upward at the middle of the tank and 25 between the baffle plates.

5. In apparatus of the character stated, the combination of a fluid containing tank having an inlet at the top and an outlet below the fluid level therein, oppositely acting 30 disintegrating propellers rotating within the tank for producing violently opposed currents of the fluid therein, and wherein further, the tank is provided with transverse baffle partitions arranged at a higher level 35 than the propellers and spaced apart at a place intermediate of the oppositely acting propellers, whereby the fluid currents from the two propellers, respectively below the baffle partitions are forcibly intermingled 40 and the fluid mixture subdivided and recirculated above the baffle partitions back to the propellers.

6. In apparatus of the character stated, the combination of a fluid containing tank 45 having an inlet at the top and an outlet below the fluid level therein, oppositely acting disintegrating propellers rotating within the tank for producing violently opposed currents of the fluid therein, and wherein further, the tank is provided with transverse 50 baffle partitions spaced apart between the propellers and substantially below the inlet to the tank, and passageways are provided for the return of the fluid from said space between the partitions above the same and to the receiving sides of the propellers.

7. In apparatus of the character stated, the combination of a fluid containing tank 60 having an inlet at the top and an outlet below the fluid level therein, oppositely acting disintegrating propellers rotating within the tank for producing violently opposed currents of the fluid therein, and wherein further, the tank is provided with transverse 65 baffle partitions spaced apart between the

propellers and below the inlet to the tank, and the outlet from the tank is arranged below the inlet and at a lower level than the baffle partitions.

8. In apparatus of the character stated, 70 the combination of a fluid containing tank having an inlet at the top and an outlet below the fluid level therein, oppositely acting disintegrating propellers rotating within the tank for producing violently opposed currents of the fluid therein, and wherein further, the tank is provided with transverse baffle partitions spaced apart between the propellers and below the inlet to the tank, and the outlet from the tank is arranged below the inlet 80 and at a lower level than the baffle partitions, said outlet provided with two oppositely inclined apertured plates for screening the outwardly flowing fluid.

9. In apparatus of the character stated, 85 the combination of a fluid containing tank having an inlet at the top and an outlet below the fluid level therein, oppositely acting disintegrating propellers rotating within the tank for producing violently opposed currents of the fluid therein, and wherein further, the oppositely acting propellers include a plurality of each kind arranged in sets, and 90 separate tunnels within the tank in alinement for the respective sets of propellers and said tunnels being open at each end to the upper portion of the tank.

10. In apparatus of the character stated, the combination of a fluid containing tank having an inlet at the top and an outlet below the fluid level therein, oppositely acting 100 disintegrating propellers rotating within the tank for producing violently opposed currents of the fluid therein, and wherein further, the oppositely acting propellers include a plurality of each kind arranged in sets, and 105 separate tunnels within the tank in alinement for the respective sets of propellers and said tunnels being open at each end to the upper portion of the tank, and wherein further, the inlet and outlet of the tank are arranged in substantial vertical alinement between the adjacent ends of the tunnels.

11. In apparatus of the character stated, the combination of a fluid containing tank having an inlet at the top and an outlet below the fluid level therein, oppositely acting disintegrating propellers rotating within the tank for producing violently opposed currents of the fluid therein, and wherein further, the propellers are provided with blades 115 provided on their edges with relatively sharp serrations.

12. In apparatus of the character stated, a fluid containing tank having an inlet at its 120 top and an outlet below the fluid level therein, combined with means for introducing fluid to the tank to compensate for that removed through the outlet, means for producing 125 violently opposed currents of fluid, and 130

guiding means for said opposing currents comprising substantially horizontal passages uniting in a substantially vertical passage.

13. The invention according to claim 12, wherein further, the inlet is arranged above the vertical passage of the guiding means for the opposed currents and the outlet is arranged below the guiding means.

14. In apparatus of the character stated, an integral structure having a large tank capacity and a submerged tunnel having its opposite ends in communication with the tank portion above the tunnel whereby the water and contents may circulate continuously through the tunnel in one direction, said structure having an inlet at the top for introducing pulp material in bulk into the tank and having a controlled outlet from its lower portion, combined with disintegrating means arranged in the tunnel for forcing the fluid stock into violent agitation and disintegration while passing through the tunnel and causing the same to circulate through the tank and repeatedly through the tunnel in a substantially continuous manner.

25 In testimony of which invention, I hereunto set my hand.

HARRY LIEBECK.
